UNITED STATES PATENT OFFICE.

JAMES MARSDEN, OF WIGAN, ENGLAND.

DESIGN FOR A PATTERN-CHART.

SPECIFICATION forming part of Design No. 29,198, dated August 9, 1898.

Application filed June 8, 1898. Serial No. 682,955. Term of patent 14 years.

To all whom it may concern:

Be it known that I, JAMES MARSDEN, a subject of the Queen of Great Britain and Ireland, and a resident of Wigan, in the county 5 of Lancaster, England, have invented and produced a new and original Design for a Pattern-Chart, of which the following is a specification, reference being had to the accompanying drawing, forming a part thereof.

o The drawing is a plan view of a pattern-chart, showing my new design.

As shown in the drawing, the leading or material feature of my design consists in a pattern-chart having represented thereon the 5 novel arrangement of patterns for a man's lounge suit, as now described. At one end of the pattern-chart is shown the under side A of the trousers, having inlays a and marks a' and a'' and scale a^3 , top side of the trousers o B having marks b' and b'' , joining part C, trousers-pocket facing D, jacket-pocket flap E, breast-pocket facing F, inside collar G, fly

H, ticket-pocket flap I, vest-pocket welt J, breast-pocket welt K, and vest-facing and jacket-facing M and M'. At the other end of 25 the pattern-chart is shown the top side N of sleeve and bottom side N' of sleeve, each having marks n, vest-bottom facing O, jacket-back P, having inlay p, jacket fore part Q, neck-piece R of vest, outside collar S, pocket-facing T, and vest fore part U. 30

Having thus described my invention, the following is what I claim as new therein and desire to secure by Letters Patent:

The design for a pattern-chart substantially 35 as herein shown and described.

In witness whereof I have hereunto signed my name, this 12th day of May, 1898, in the presence of two subscribing witnesses.

JAMES MARSDEN.
